DESIGN FOR A HAIR DRIER

Rudolph L. Meltzer, Racine, Wis., assignor to Master Appliance Mfg. Co., Racine, Wis.

Application December 11, 1948, Serial No. 150,107

Term of patent 14 years

(Cl. D86—10)

To all whom it may concern:

Be it known that I, Rudolph L. Meltzer, a citizen of the United States, residing at Racine, in the county of Racine and State of Wisconsin, have invented a new, original, and ornamental Design for a Hair Drier, of which the following is a specification, reference being had to the accompanying drawing, forming part thereof.

Figure 1 is a perspective view of a hair drier, showing my new design, the view illustrating one side and the back of the hair drier.

I claim:

The ornamental design for a hair drier, as shown.

RUDOLPH L. MELTZER.
